ARTICLE DISPENSING DEVICE

Arthur C. Hopkins, Tupper Lake, N. Y., and
Samuel N. Hope, Wauwatosa, Wis., assignors
to Oval Wood Dish Corporation, Tupper Lake,
N. Y., a corporation of Delaware

Application February 10, 1940, Serial No. 318,242

9 Claims. (Cl. 312—63)

The present invention relates to article-dispensing devices and more particularly to dispensers for spoons and similar articles.

An object of the invention is to provide an improved dispensing device of simple and durable construction for delivering articles such as wooden spoons and the like one at a time and in a sanitary manner.

Another object of the invention is to provide a dispensing device which is reliable in operation notwithstanding possible non-uniformity of the articles incident to warping or other causes.

A further object is to provide a dispensing device which is readily adapted for use with articles of different length.

A still further object is to provide a dispensing device which is capable of easy assembly and inexpensive manufacture.

The invention further consists in the several features hereinafter described and claimed.

In the accompanying drawings,

Fig. 1 is a front elevation of a spoon-dispensing device constructed in accordance with the invention, the device having a base to permit table mounting;

Fig. 2 is a side elevation of the device, an open position of a swingable front cover thereof being shown in dotted lines;

Fig. 3 is a rear elevation;

Fig. 4 is a top view;

Fig. 5 is a front elevation, the cover being open, and parts being broken away and parts being shown in section;

Fig. 6 is a top view, the cover being shown in transverse section and the base and other parts being omitted, a projected position of a spoon handle being shown in dotted lines;

Fig. 7 is a view similar to Fig. 6, but showing the device adapted for dispensing a longer type of spoon;

Fig. 8 is a transverse sectional elevation taken generally along the line 8—8 of Fig. 1, a projected position of a spoon handle being shown in dotted lines;

Fig. 9 is a sectional view taken generally along the line 9—9 of Fig. 5, the cover being open and the base being omitted;

Fig. 10 is a bottom view with the base omitted, parts being broken away and parts being shown in section;

Fig. 11 is a detail sectional elevation taken generally along the line 11—11 of Fig. 9;

Fig. 12 is a detail sectional elevation taken generally along the line 12—12 of Fig. 9, the cover being closed and a depressed position of a dis-

pensing lever being shown in dotted lines, and

Fig. 13 is a side elevation of the device with the base removed, the device being mounted on a vertical supporting wall, and an open position of the cover being shown in dotted lines.

In these drawings, 20 designates an upright casing of generally rectangular shape and comprising a vertical back wall 21, opposite vertical side walls 22 each with inturned upper and lower

front flanges 23 and 24, respectively, a horizontal article-supporting bottom wall or platform 25 spaced above the lower end of the casing, and a front wall or skirt 26 extending downwardly from the front edge of the bottom wall. The back

wall, side walls and front flanges are preferably formed by a sheet metal plate suitable bent to shape, and the bottom wall and front wall are preferably formed by another bent sheet metal plate. The front wall or skirt is riveted or otherwise secured to the lower front flanges 24 and has rearwardly bent vertical end flanges 27 lapping inwardly offset portions of the side walls 22 and secured thereto by horizontally aligned rivets 28.

25 A U-shaped frame or bracket 29 has its intermediate portion spot-welded or otherwise secured to the rear face of the front wall or skirt 26 and has its legs extending rearwardly to the front face of the back wall 21, the latter having forwardly projecting lugs 30 engaging the lower edges of these legs.

20 The casing is provided with a cover or closure 31 which preferably comprises a sheet metal plate bent to form a vertical front wall 32, a top wall 33 and opposite side flanges 34, the latter being adapted to lap the side walls 22 of the casing. At their lower ends the side flanges 34 have downwardly projecting ears 35 which are embossed at their inner sides to bear on the end flanges 27 of the casing and are pivotally secured thereto by the aligned rivets 28. The cover

35 is releasably held in its closed position by a friction catch 36 secured to the front face of the upper portion of the casing back wall 21, the catch cooperating with an opening 37 formed in the cover top wall. The upper edge of the casing back wall forms a stop engageable with the rear edge of the cover top wall. The casing and its cover form an article-receiving container. When the cover is in its closed position, the lower edge of its front wall 32 is spaced above the plane of the bottom wall or platform 25 to form an article-delivery slot 38, as hereinafter more fully described.

30 In many instances it is desirable to support

40 the cover in its closed position, the lower edge of its front wall 32 being supported by a stop 39 which is engageable with the upper edge of the bottom wall or platform 25. The cover is releasably held in its closed position by a friction catch 40 secured to the front face of the upper portion of the casing back wall 21, the catch

45 catch cooperating with an opening 41 formed in the cover top wall. The upper edge of the casing back wall forms a stop engageable with the rear edge of the cover top wall. The casing and its cover form an article-receiving container. When the cover is in its closed position, the lower edge of its front wall 32 is spaced above the plane of the bottom wall or platform 25 to form an article-delivery slot 38, as hereinafter more fully described.

50 In many instances it is desirable to support

the casing on a table or counter, and for this purpose the casing is mounted on a base 39, such as the hollow rectangular metal casting, preferably provided with rubber feet 40. The lower end of the casing fits in a shallow rectangular recess 41 formed in the upper face of the base and is detachably secured to the base by screws 42 engaging eared portions of the frame or bracket 29. A stop lug 43 is formed on the front portions of the base to limit the opening movement of the cover to an approximately horizontal position, as shown by dotted lines in Fig. 2.

The casing is also adapted to be mounted on a vertical supporting wall 44, as seen in Fig. 13, in which event the base 39 is removed. The back wall of the casing is engageable with the supporting wall and is provided with openings 45 to receive screws 46 or other fastening members. When the cover is opened it is swung downwardly to the freely suspended position shown by dotted lines in Fig. 13.

As hereinafter more fully set forth, the casing forms a magazine for elongated articles to be dispensed, here exemplified by ice cream spoons S, Figs. 5 and 6, and by similar but somewhat longer soda spoons S', Fig. 7. These spoons may be formed by pressing thin wooden blanks to the desired shape, and are discardable after use.

A flanged sheet metal spacer bar 47 is spot-welded or otherwise secured in a vertical position to the front face of the casing back wall 21. A vertical sheet metal guide bar 48 of Z-shaped cross-section is detachably secured by screws 49 to the front face on the spacer bar and forms therewith a vertical guide channel 50 adapted to receive the handle ends of a stack of the spoons S. The nested bowl portions of the spoons are inverted and are confined in a vertical channel 51 formed by one of the flanged side portions of the casing. The lower ends of front flanges 23 of the casing and the lower edge of the front flange of the guide bar 48 are spaced above the horizontal plane of the platform 25 to permit forward passage of the lowermost spoon. As hereinbefore noted, the lower edge of the cover front wall 32 is spaced above the platform plane to form the delivery slot 38. This slot is preferably of the non-linear shape shown in Figs. 1 and 9, one end portion 52 of this edge being arched to provide clearance for the bowl portion of the lowermost spoon during withdrawal of this spoon. The depth or thickness of the container formed by the casing and its cover is only slightly greater than the width of the bowl portions of the spoons.

When it is desired to dispense the soda spoons S' of Fig. 7 the guide bar 48 is removed, allowing the handle ends of the stacked spoons S' to be guided by one of the flanged side walls 22 of the casing and by the front face of the spacer bar 47, as indicated in Fig. 7. The width of the casing is only slightly greater than the length of the spoons S'.

The substantially fiat handle portion of the lowermost spoon is approximately level and rests on a rib 53 extending across the platform 25 from front to rear, and the bowl tip of the lowermost spoon rests on the flat face of the platform, the latter forming a bearing surface for this spoon. In order to prevent accidental tilting or disarrangement of the spoons a ridge 54 is formed on the platform to underlie the bowl portion of the lowermost spoon, this ridge extending forwardly from the rear edge of the platform to about

midway between the front and rear edges of the platform.

An ejector 55 is provided for pushing the handle portion of the lowermost spoon forwardly through the delivery slot 38 in an angular path, the spoon swinging about its bowl end to an oblique position, as indicated by dotted lines in Figs. 6 and 7. By this movement the handle portion of the spoon is exposed at the front of the casing to permit manual withdrawal of the spoon without danger of contaminating the bowl portion of the spoon, thus avoiding the necessity for wrapping the individual spoons. The ejector is preferably in the form of a reciprocatory lever which extends below the platform in approximately parallel relation to the length of the platform and is pivotally secured to the platform by a vertical pivot stud 56 near the end of the platform supporting the bowl ends of the spoons. The free end portion of the lever slidably rests on the upper edge of one of the legs of the frame 29 and has an upturned pusher projection or tongue 57 extending through a slot 58 formed in the platform near and approximately parallel to the handle-supporting rib 53, the projection extending high enough to engage the rear edge of the handle of the lowermost spoon but not the following spoon. The ejector lever is normally urged rearwardly by a V-shaped torsion spring 59 having a coiled intermediate portion surrounding the pivot stud 56 and having projecting arms one of which engages the rear wall of the frame 29 and the other of which engages a downturned lug 60 on the ejector lever. An angular actuating lever 61 has a portion projecting forwardly through a vertical slot 62 formed in the front wall or skirt 26 of the casing and is pivotally secured by a horizontal pivot member 63 to one leg of the frame 29. An upwardly projecting arm 64, Fig. 12, formed on the rear portion of the actuating lever is engageable with the downturned lug 60 of the ejector lever for swinging the ejector lever forwardly on a dispensing stroke. The upper edge of the ejector lever projection or tongue 57 has a path of travel which lies in a horizontal plane.

In order to insure proper dispensing of the spoons, one at a time, a leaf spring 65 is secured at its laterally notched upper end to the inner face of the cover, as by a lugged mounting plate 66 spot-welded to the cover, and has its free lower end engageable with the front edge of the handle portion of the second lowest spoon adjacent to the front end of the spoon-supporting rib 53.

The back wall of the casing has a vertical inspection slot 67 for enabling the user or attendant to determine when the dispenser requires replenishment.

In loading the dispensing device the cover is opened and a stack of spoons is lowered into the open-topped casing. Preferably the spoons are supplied in a suitably tied bundle, so as to facilitate handling and to avoid contamination of the spoons, the tying string or band (not shown) being removed after the stack is in place. During opening of the cover the arched edge 52 clears the actuating lever 61. After loading of the device the cover is swung upwardly to its closed position, and the device is ready for use.

In operation, a user desiring a spoon depresses the actuating lever 61, causing the ejector lever 55 to swing forwardly against the action of its return spring 59. The projection 57 of the ejector lever pushes the han-

idle portion of the lowermost spoon forwardly through the delivery slot 38, the spoon swinging about its bowl portion which remains housed within the casing, and the following spoon being restrained against forward dispensing movement by the lower end of the leaf spring 65. The partially ejected lowermost spoon is supported and retained in its angularly projecting position by the platform 25 and also by the superposed spoons. The ejector lever is suitably limited in its forward movement, as by its engagement with the front end of the slot 58. The actuating lever 61 is then released, the spring 59 returning this lever and the ejector lever to their retracted positions. The user then grasps the free end of the projected handle portion of the lowermost spoon and pulls the spoon forwardly through the delivery slot, thereby releasing the spoon from the stack. The following spoon of the stack then drops to the platform in readiness for the next dispensing operation. The nested relation of the bowl portions of the spoons aids in retaining the second last spoon in the casing during the withdrawal of the lowermost spoon, although flat spoons will also be properly dispensed.

The spoon-engaging projection 57 of the ejector lever has its path of movement adjacent to the narrow rib 53 which supports the handle portion of the lowermost spoon. By this construction accurate supporting and feeding of the spoons is assured, notwithstanding the use of the device with spoons of different length and notwithstanding possible non-uniformity of the spoons incident to warping or other causes. As the plane of the path of travel of the upper edge of the ejector lever tongue 57 is approximately parallel to the thin flat handle portion of the lowermost spoon, this tongue will have a firm impelling engagement with the rear edge of this handle portion without danger of engaging the following spoon. The rough or fibrous surfaces of the wooden spoon handles tend to cause the lowermost spoon to frictionally engage the superposed following spoon and to exert a forward dragging and tipping action on the following spoon during the dispensing of the lowermost spoon. The stop spring 65, however, permits the following spoon to yield forwardly a short distance during the withdrawal of the lowermost spoon and thus relieves the frictional engagement and the tipping tendency.

While the device is here shown to be used for dispensing spoons, it is also capable of use in dispensing various other articles including forks and paddles. Although it is preferred to provide the casing with the protecting cover, the dispensing device is also operable without the cover. The device is preferably mounted in a vertical position, as shown, but it can also be mounted in other positions such as various inclined positions. If desired, any well known type of follower or feeder, not shown, may be employed for urging the stack or succession of articles toward dispensing position, as when the articles are to be fed horizontally or in an upward direction.

What we claim as new and desire to secure by Letters Patent is:

1. A dispenser for articles such as spoons and the like, comprising means for supporting a stack of the articles, and ejecting means for swinging an endmost article laterally of the stack to project one end portion of said article from the stack in position for permitting withdrawal of such article, said dispenser including a bearing surface

against which the other end portion of said endmost article is held to support and releasably retain said article in its swingably projected position.

5 2. A dispenser for elongated articles such as spoons and the like, comprising a casing adapted to receive therein a stack of the articles and having guides for the opposite ends of the stacked articles, an intermediate guide detachably mounted in said casing between said first-named guides for adapting the casing to receive a stack of shorter articles extensible between said intermediate guide and one of said first-named guides, said casing having a discharge space to permit lateral dispensing of the foremost article therethrough, and means for effecting the lateral dispensing of said foremost article.

20 3. A dispenser for elongated articles such as spoons and the like, comprising a casing adapted to receive therein a stack of the articles and having guides for the opposite ends of the stacked articles, an intermediate guide detachably mounted in said casing between said first-named guides for adapting the casing to receive a stack of shorter articles extensible between said intermediate guide and one of said first-named guides, and common ejecting means operable on either the long or the short articles for projecting an endmost article from the stack, said casing having a discharge opening for the articles.

25 4. A dispenser for elongated articles such as spoons and the like with arched end portions, comprising a casing adapted to receive therein a stack of the articles and having an abutment engageable by the foremost article, said casing having a delivery space to permit lateral dispensing of the foremost article therethrough, and said casing having a projection engageable by the concave side of the arched end portion of the foremost article for limiting tipping movement of the stacked articles, and ejecting means for said articles.

30 5. A dispenser for thin elongated articles such as spoons and the like, comprising means for supporting a stack of the articles, means for displacing the foremost article laterally of the stack and for sliding said foremost article along the underside of the second foremost article resting thereon, and a resiliently mounted member yieldably engageable with the front edge of the second foremost article of the stack to prevent tilting disarrangement of the stacked articles and to restrain lateral discharge of said second foremost article, said resiliently mounted member being out of the discharge path of the foremost article and permitting a limited lateral yielding of said second foremost article by the frictional engagement between said two articles during the lateral displacement of said foremost article.

35 6. A dispenser for thin elongated articles such as spoons and the like, comprising means for supporting a stack of the articles and including an abutment engageable flatwise by the foremost article, normally retracted ejector means for displacing the foremost article laterally of the stack and having an impelling portion engageable with the rear edge of said foremost article, said abutment being adjacent to the path of said impelling portion and being engageable with a relatively small area of the foremost article, and the free edge of said impelling portion having a path of travel lying in a plane substantially parallel to the lateral path of travel of the foremost article.

7. A dispenser for elongated articles such as spoons and the like, comprising a casing adapted to receive therein a stack of the articles and having a bottom portion on which the lowermost article is adapted to rest, said casing having a discharge opening for the articles, and ejecting means for laterally displacing the foremost article of the stack and comprising a forwardly movable lever extending below said bottom portion and pivoted on said casing to swing about an axis transverse to the plane of said bottom portion, said lever having an upwardly projecting impelling portion engageable with the rear edge of the lowermost article.

8. A dispenser for articles such as spoons and the like, comprising a casing adapted to receive therein a stack of the articles and having a bottom wall for supporting said stack and a front wall projecting downwardly from said bottom wall, said casing having a discharge opening for the articles, and ejecting means for laterally displacing the lowermost article of the stack and including an ejecting lever for said article ex-

tending below said bottom wall and a manually operable actuating lever extending through said front wall, said ejecting lever having a pivotal axis transverse to the plane of said bottom wall.

9. A dispenser for elongated articles such as spoons and the like, comprising means for supporting a stack of the articles, and ejecting means for swingably displacing an endmost article laterally of the stack to project one end of said article from the stack in position for permitting withdrawal of such article, said ejecting means comprising a forwardly movable lever extending in a direction generally parallel to the position of said endmost article and pivoted on said supporting means to swing about an axis substantially at right angles to the lateral path of travel of said endmost article, said lever having a laterally projecting impelling portion engageable with the rear edge of said endmost article.
